UNITED STATES PATENT OFFICE.

WILLIAM T. WATERSTRAAT, OF CHICAGO, ILLINOIS.

REVERSIBLE WINDOW.

SPECIFICATION forming part of Letters Patent No. 627,164, dated June 20, 1899.

Application filed October 1, 1898. Serial No. 692,422. (No model.)

To all whom it may concern:

Be it known that I, WILLIAM T. WATERSTRAAT, a citizen of the United States, residing at Chicago, in the county of Cook and State 5 of Illinois, have invented a new and useful Improvement in Reversible Windows, of which the following is a specification.

My invention relates more particularly to the class of reversible windows in which the 10 sash is pivotally supported at its side stiles between sliding stiles confined in grooves in the window-frame to adapt the sash to be swung through a vertical plane to render its outer side accessible by presenting it to the interior of the apartment containing the window 15 for convenience in cleaning, glazing, and painting it, and the like.

One of my objects is to provide for supporting the sash, to render it reversible, an improved construction of pivot device whereby it shall not protrude undesirably beyond the inner surface of the window and whereby more especially it shall afford thorough closure to the space in the plane it occupies between the side stile of the sash and the adjacent sliding stile, thus to exclude draft and prevent the light shining through said space. My further object is to provide for the reversible sash an automatic lock against accidental turning of the sash on its pivots.

Referring to the accompanying drawings, Figure 1 is a view in elevation of the inner side of a window having its lower sash equipped with my improvements; Fig. 2, an enlarged section taken at the line 2 on Fig. 1 and viewed in the direction of the arrow; Fig. 3, a similar section taken at the line 3 on Fig. 1 and viewed in the direction of the arrow; Fig. 4, a similar section taken at the line 4 on Fig. 1 and viewed in the direction of the arrow; Fig. 5, an enlarged section taken at the line 5 on Fig. 3, viewed in the direction of the arrow and showing one of the pivot-plates in side elevation; Fig. 6, an enlarged section taken at the line 6 on Fig. 3, viewed in the direction of the arrow and showing the other pivot-plate in side elevation; Fig. 7, a perspective view of the upper portion of a sliding stile surmounted by the catch portion 50 of the automatic lock; Fig. 8, a similar view

of a portion of the top sash-rail surmounted by a spring-latch of the automatic lock for engaging with the catch; Fig. 9, a perspective view of a sliding stile, and Fig. 10 a similar view of a sash-stile.

55

A is a window-frame of any suitable general construction.

B is the lower sash, and B' the upper sash.

Only the lower sash is shown in the drawings as equipped with my improvements, 60 though they are also applicable to the upper sash. Moreover, it may be here stated that my improved pivot device hereinafter described may be used with advantage on reversible windows, in which the sash is pivoted 65 at its upper and lower ends to swing on a vertical axis.

In the vertical grooves *r r*, provided in the opposite sides of the frame A, are confined, respectively, the sliding stiles C C, each provided with an offset extending throughout the length of its exposed side, forming a longitudinal shoulder *p*, facing the inner side of the window-frame. From a point about midway between the ends of each sliding stile, abutting against the shoulder *p*, there extends to the lower end thereof a strip *v*, thicker than the shoulder *p*, to protrude beyond it a longitudinal shoulder *o*, facing toward the outer side of the window-frame. Near the transverse center of each sliding stile C there is formed in its exposed side to extend backward or outward from its face a recess *n*, projecting into the shoulder *p* and of a form adapting it to receive a pivot-plate D, here- 75 inafter described.

In the side which opposes the exposed side or face of a sliding stile of each stile C' of the window-sash there is provided, extending, like the offset on a sliding stile, from the inner surface of the stile to or beyond its longitudinal center, an offset forming a shoulder *p'* of the length of the sash-stile and facing the inner side of the sash. From a point about midway between the ends of each sash-stile C', abutting against the shoulder *p'*, there extends to the upper end thereof a strip *v'* thicker than the shoulder *p'* and to protrude beyond it a longitudinal shoulder *o'*, facing toward the outer side of the window-frame. Near the 80 85 90 95 100

transverse center of each sash-stile C' there is formed in its exposed side to extend backward or outward from its front a recess n' of a form adapting it to receive a pivot-plate D', hereinafter described.

The preferred form of each of the pivot-plates D and D' is that shown, involving flat sides having screw-holes, a straight front or inner edge provided with a flange m, straight 10 upper and lower edges, as shown at t in Figs. 5 and 6, and bowed or arc-shaped back edges, as shown at t'. Near the front edges of the plates, on the faces thereof which oppose each other, are provided bosses l, the boss on 15 one of the plates having a pivot-hole and that on the other plate carrying rigidly the pivot-pin D² to enter the pivot-hole, in which it is riveted or otherwise fastened against withdrawal, but in a manner to permit the 20 plates to turn one upon the other. About the outer bowed edge t' of the pivot-plate D' there is provided a laterally-extending curved flange t'', for a purpose hereinafter described.

When the sash B is in place in its normal 25 upright position, with the pivot-plates in their recesses n n' and connected near their inner edges by the pivot-pin D², the shoulders o' on the sash-stiles abut outward or backward against and form weather-excluding rabbet-30 joints, with the upper parts of the shoulders p on the sliding stiles, and the lower parts of these shoulders (below the pivot-plate recesses) abut in a forward or inward direction against and form weather-excluding rabbet-35 joints, with the shoulders o on the sliding stiles. The flanges m on the pivot-plates meet at their opposing edges, and at their opposite outer edges they respectively overlap to a slight extent the faces of the sliding stiles 40 and sash-stiles, and the bowed flange t'' on each plate D' conforms to and fits in the correspondingly-shaped back of the portion of the corresponding sliding-stile recess n, which extends in the shoulder p, which back it overlaps, thereby closing the back of the space 45 between coöperating pivot-plates and excluding draft and light between them.

On the upper end of a sliding stile (or on each sliding stile, as shown) is provided a 50 rigid catch k, and to coöperate with each catch there is provided on the upper rail of the sash B a latch-finger i, pivoted between its ends to protrude at one end into the path of the catch and controlled by a spring i' to 55 give it a tendency to engage with the catch. The spring-latch and catch thus form members of the automatic lock, the latch being normally behind the catch to abut against it, and thus prevent the sash from being turned 60 on its pivots, and being releasable by turning the latch on its pivot above the catch. The top of the catch is beveled, as shown at k', to present an inclined plane to the latch when brought against it by righting the sash and 65 permit the latch to clear the back k' and spring into engagement with the catch.

To turn the sash B, the latches i are depressed to release them from the catches k, when the sash may be swung upon its pivots, and the pivoting of the plates D and D' near 70 their front edges enables the sash to be turned about completely with great convenience. In returning the sash to its normal upright position the latches slide over the inclined backs of the catches, and on clearing them spring 75 into locking engagement with the catches to secure the sash against being accidentally turned.

What I claim as new, and desire to secure by Letters Patent, is—

1. In a reversible window, the combination with the sliding stiles confined in grooves in the window-frame, and the window-sash, of recesses in the faces of the sliding stiles, pivot-plates secured in said recesses, pivot-plates 85 secured to the sash-stiles and having flanges on their back edges overlapping the sliding-stile recesses, and pivot-pins connecting the sash and sliding-stile plates near their front edges, substantially as described.

2. In a reversible window, the combination with the sliding stiles confined in grooves in the window-frame, and the window-sash, of recesses in the faces of the sliding stiles, pivot-plates secured in said recesses, pivot-plates 95 secured to the sash-stiles having flanges on their back edges overlapping the sliding-stile recesses, pivot-pins connecting the sash and sliding-stile plates near their front edges, and meeting flanges on the front edges of each 100 pair of plates overlapping the adjacent stiles, substantially as described.

3. In a reversible window, the combination of sliding stiles confined in grooves in the window-frame and having longitudinal shoulders p near the centers of their faces, recesses near their transverse centers extending into said shoulders and shoulders o extending from said recesses to the lower ends of said stiles and facing oppositely to said shoulders p, 110 pivot-plates in said recesses, a window-sash having its stiles provided with longitudinal shoulders p' near the centers of their faces, recesses near their transverse centers extending into said shoulders p' and shoulders o' extending from the recesses to the lower ends of the sash-stiles and facing oppositely to said shoulders p', pivot-pins connecting the sash and sliding-stile plates near their front edges 120 on the sash-stiles overlapping the recesses in the sliding stiles, substantially as described.

4. In a reversible window, the combination with the sash of means for pivotally supporting it in place, comprising a plate D having 125 a bowed edge t', a plate D' having a bowed edge t' provided with a curved flange t'', and a pivot-pin D² connecting said plates near their forward edges, substantially as and for the purpose set forth.

5. In a reversible window, the combination with the sliding stiles confined in grooves in

the window-frame, and the window-sash, of recesses in the faces of the sliding stiles, pivot-
plates secured in said recesses and having the straight, flanged front edges and bowed rear
edges, pivot-plates secured to the sash-stiles and having the straight, flanged front edges and bowed and flanged rear edges, and pivot-

pins connecting the sash and sliding-stile plates near their front edges, substantially as described.

WILLIAM T. WATERSTRAAT.
